UNITED STATES PATENT OFFICE.

GEORGE C. ROBERTS, OF CHICAGO, ILLINOIS, ASSIGNOR TO THE TROY
LAUNDRY MACHINERY COMPANY, OF TROY, NEW YORK.

REVERSAL-GEAR.

SPECIFICATION forming part of Letters Patent No. 425,458, dated April 15, 1890.

Application filed July 23, 1889. Serial No. 318,382. (No model.)

To all whom it may concern:

Be it known that I, GEORGE C. ROBERTS, of Chicago, in the county of Cook and State of Illinois, have invented certain new and useful 5 Improvements in Reversing-Gears; and I do hereby declare that the following is a full, clear, and exact description thereof, reference being had to the accompanying drawings, and to the letters of reference marked thereon, 10 which form a part of this specification.

This invention relates to improvements in reversing-gears for use upon washing-machines and in similar situations where it is desired to reverse the motion of the moving 15 parts of a machine at regular intervals.

The reversing-gear is herein shown as applied to move the reciprocating parts of a belt-shifting device; but the features of construction constituting the invention may be applied 20 to friction-clutches or other similar devices.

The invention consists in the matters hereinafter described, and pointed out in the appended claims.

In the accompanying drawings, illustrating 25 my invention, Figure 1 is a side view of an apparatus embodying the same applied to the end of a washing-machine of that class consisting of a cylindric exterior shell or casing provided with an interior oscillating drum. 30 Fig. 2 is an end elevation of the part shown in Fig. 1. Fig. 3 is a top or plan view of said parts. Fig. 4 is a detail section taken upon line 4-4 of Fig. 1. Figs. 5 and 6 illustrate the parts shown in Fig. 4 in changed position. 35 Fig. 7 is a detail section taken upon line 7-7 of Fig. 2. Fig. 8 is a perspective view of the cap for the outer shaft-bearing. Fig. 9 is a perspective view of the outer end of the arm which supports the outer end of the shaft. 40 Fig. 10 is a perspective view of the adjustable frame which sustains the main working parts of the device. Fig. 11 is a perspective view of the slide-bar by which the belt and shifter-arms are actuated. Fig. 12 is a perspective 45 view of the cam-plate by which motion is given to said slide-bar. Fig. 13 is a section similar to Fig. 4, showing a modified construction of the parts.

As illustrated in said drawings, A is the 50 exterior casing or shell of a washing-machine, and A' the main shaft thereof, which passes

through the shell and supports a perforated oscillating cylinder arranged in a manner heretofore common and well known.

A² is a gear-wheel attached to the shaft A' 55 outside of the head of the machine, by which oscillatory movement is given to said shaft.

B is a shaft arranged parallel with the shaft A', mounted at one end in a bearing upon the head of the machine A and at its opposite end 60 in a bearing b upon the end of the bracket B', which is attached to the head of the machine in the manner illustrated. Said shaft B is provided at a point adjacent to the head of the machine with a pinion B², which inter- 65 meshes with the gear-wheel A² upon the shaft A'.

C is a fixed pulley attached to the shaft B, and C' C² are loose pulleys mounted to turn freely on said shaft at opposite sides of said 70 fixed pulley C, and C' C² are driving-belts on said pulleys. Upon said shaft B, between the said fixed and loose pulleys and the outer bearing b, is located a sleeve D', which is attached to the hub of the loose pulley C² and 75 is provided with a worm D. The sleeve D' is loose on the shaft and turns with the loose pulley C². It follows from this construction that the said worm is driven by said loose pulley, and in order that said worm shall be 80 constantly driven, even when the driving-belt C' is driving the fixed pulley, said belt is made a little wider than the other belt C², so that the edge of the said belt C' will lap slightly over the pulley C², and thus keep the 85 same in motion at all times. The sleeve D' is conveniently connected with the hub of the loose pulley C² by means of a clutch-connection d, as clearly shown in the drawings, Fig. 1. Said worm D intermeshes with a 90 worm-wheel E, which is located above the shaft B, with its axis of rotation at right angles with the said shaft. Said worm-wheel is mounted upon a frame F, Fig. 10, which sustains the principal operative parts of the de- 95 vice. Said frame F carries the slide-bar and belt-shifting arms or loops thereon, which engage the belts, and to enable said frame to be moved or shifted in its angular position to correspond with the location of the belts 100 it is pivotally sustained in such manner that it may be adjusted in angular position by

turning about the axis of the shaft B. For this purpose said frame is provided with a socket F', Figs. 1, 4, and 10, adapted to fit over or embrace a tubular inward extension 5 b' of the outer shaft-bearing b, Fig. 7. Said socket F' is split at one point and provided with a clamp-bolt f, by which it may be closed against the extension b' for holding the frame F in a desired angular position. Said cylindric 10 extension b' is conveniently fixed upon or integral with the cap b² of the said bearing b, in the manner clearly shown in Fig. 8. Said frame F is provided at its upper part with two guide-apertures f' f', Fig. 10, through 15 which is inserted a horizontal sliding bar G, arranged parallel with the shaft B. Said bar is provided at its end adjacent to the fast and loose pulleys with oppositely-extending arms G' G², at the outer ends of which are 20 attached adjustable loops g g', which engage the driving-belts C³ C⁴.

H is a cam-plate, which is located adjacent to and parallel with the worm-wheel E and is supported by and adapted to move horizontally 25 with the slide-bar G, and also has a sliding movement upon the bar in a direction transverse to the latter. To secure this movement of the said cam-plate H, the latter is provided at its upper part with two horizontally-arranged plates or arms h h', which engage the upper and lower sides of the slide-bar G, which latter is provided with a transverse guide-slot g², Figs. 3, 6, and 11, adapted 30 to receive one of the arms h. Said cam-plate 35 is provided on its face adjacent to the worm-wheel with two opposite projections or ribs H' H', forming cam-surfaces h² h², arranged at right angles to the face of the plate and adapted for engagement with a stud or pin e, 40 which is secured in and projects from the face of the worm-wheel E. Said cam-surfaces h² h², Figs. 1 and 12, are arranged horizontally opposite each other and are at a greater distance apart at their upper and lower ends than 45 at their middle parts. This construction enables the pin or stud e to act upon the cam-surface with the effect of moving the cam-plate in the same manner when the stud is turning in either direction, the said pin operating 50 upon the upper right-hand cam-surface and lower left-hand cam-surface when the worm-wheel is turned to the right, and acting upon the upper left-hand cam-surface and lower right-hand cam-surface when said 55 wheel is turning toward the left. Said cam-surfaces are adapted for engagement with and disengagement from the said pin or stud e by a bodily movement of the cam-plate toward and from the worm-wheel E, this movement being afforded by the sliding of the cam-plate H laterally upon the slide-bar G, as hereinbefore described. Such bodily movement of the cam-plate therefore enables the machine to be stopped and started when desired, the releasing of the cam-plate from the pin at the time both bolts are on the loose pulleys obviously affecting the stoppage of

the machine. At the side margins of the cam-plate exterior to said cam-surfaces said cam-plate is provided with two flat plates or wings 70 H² H², Fig. 12, which are flush with the edges of the flanges H' H', and which, by striking the end of the stud e, serve to prevent the cam-plate from being thrust toward the worm-wheel E when said stud is outside of the said 75 flanges. Devices for actuating the said cam-plate in the manner described are provided as follows:

I is a hand-lever by which such movement of the plate is accomplished, said hand-lever 80 being pivotally connected at its lower end with the frame F by means of a swiveled oscillating stud i, mounted on a lug F² on the hub F', Fig. 10. Said swivel-stud i, Figs. 5 and 6, is provided with an aperture head or 85 eye, through which is inserted a pivot-pin i', by which the lower end of the lever I is connected with the said stud. Said lever I is provided at its upper end with a handle I', and at a point between the handle and its 90 lower end is connected with the cam-plate H in such manner that when the said lever is swung outwardly or inwardly upon the pivot i' the cam-plate will be moved with it toward or from the worm-wheel E. The connecting 95 device for this purpose herein shown consists of a stud i² in the cam-plate, connected at its outer end with the hand-lever by means of a pivot-pin i², passing through the outer end of the said stud and through a slotted 100 opening i² in the hand-lever, Figs. 5 and 6. The said hand-lever is shown as slotted to receive the head or eye of the stud i², the pivot-pin i² being inserted through the parts of the lever at opposite sides of the said stud. The 105 cam-plate H being moved back and forth by the action of the stud e of the worm-wheel thereon to give motion to the sliding bar G, as hereinbefore described, it follows that the hand-lever I will be swung or moved back 110 and forth with the cam-plate as the latter is reciprocated, the hand-lever in this movement swinging on the swiveled stud i. The movement of the said cam-plate is, however, relatively slow, owing to the fact that it is driven 115 through the medium of the worm-wheel and worm, so that the said hand-lever may be easily grasped at any time to shift the same backward or forward for the purpose of engaging the cam-plate with or disengaging it 120 from the stud e.

It is obviously desirable that the hand-lever should be locked at the limit of its movement, so as to hold the cam-plate from being accidentally moved or shifted when the cam-plate is engaged with the stud e or released therefrom. For so securing or locking the hand-lever the same is provided with a detent J, pivoted at the upper end of the lever by means of a pivot j, located near the handle thereof, said detent being arranged to extend horizontally over the top of the cam-plate and having a downturned end or arm j', adapted to engage with the slide-bar G. Said

detent has an upwardly-extending arm or handle J' , arranged in such position that it may be easily grasped by the hand at the time of actuating the lever I . The downturned end j' of said detent J is adapted to engage the rear face or edge of the bar G when the cam-plate is interlocked with the stud e , and to engage a hole j^2 in the bar G when said cam-plate is in position remote from the worm-wheel, as shown in Fig. 6. The detent J is preferably thrown downwardly or into position to engage the slide-bar G by means of a spring herein shown as having the form of a spiral spring j^3 , located between the upper end or handle I' of the lever I and the handle J' of the detent. The handles I' of the hand-lever and J' of the detent are conveniently placed close together and rounded on their outer surfaces, so that they may both be grasped at the same time when it is desired to move the lever I , it obviously being necessary that the detent J should be disengaged from the slide-bar G whenever the said lever I is moved. The horizontal arms $h\ h'$ of the cam-plate II are provided with slots or recesses $h^3\ h^4$, Fig. 12, in which the downturned end j' of the detent J is inserted, it obviously being necessary to extend said arms $h\ h'$ past the end of the detent in order that the arms may have bearing on the slide-bar G at the time the cam-plate is thrown backwardly away from the worm-wheel, as illustrated in Fig. 6.

K is a locking plate or bar, arranged horizontally adjacent to the upper end of the lever I and parallel with the slide-bar G . Said plate K is herein shown as supported by means of arms $K'\ K'$, which are secured to the casting F , preferably at a point over the guide-apertures $f'\ f'$ of said casting. Said plate K is provided on its inner edge with a central notch k , adapted for engagement by the lever I when the cam-plate is at the center of its stroke and the belts are held on the two loose pulleys. Said notch is made of such depth, or, in other words, its outer wall is so located, that when the hand-lever I is brought fully into the notch the detent J will engage the hole j^2 in the slide-bar G . It follows from this construction that the said hand-lever cannot be locked in its outward position, so as to hold the cam-plate II free from the stud e of the worm-wheel, until the hand-lever has fully entered the said notch k . The main purpose of the said notch k is to lock and hold the hand-lever I from being shifted in a direction to move the slide-bar G at the time the belts are on the loose pulleys and the machine not running, it being entirely obvious that in the absence of the plate K whenever the hand-lever is thrown forward into position to disengage the cam-plate from the stud e the said slide-bar G could be moved by means of the hand applied to the hand-lever I in a manner to shift the belts. At either side of the notch k said plate K is provided with two bearing surfaces or edges $k'\ k'$, arranged parallel with the bar G and located at such distance from

the said bar that when the lever I is swung outwardly into contact with the same the cam-plate II will be free from the stud e , so that the said cam-plate may be moved independently of the stud. It follows that when the hand-lever is thrown against the said surface $k'\ k'$ it may be moved along said surface by hand for the purpose of shifting the slide-bar G and the belts. It is often desirable that the belts may be shifted by hand in order to give a slight movement to the inner cylinder of the washing-machine when it is desired to turn the same a short distance to bring the door or opening thereof opposite the external door or opening of the outer casing. It will of course be seen that when the hand-lever is brought out against or near the surfaces $k'\ k'$ the detent J cannot engage the hole j^2 , so that the hand-lever cannot be locked in this position.

At the outer ends of the surfaces $k'\ k'$ are located shoulders $k^2\ k^2$, arranged at such distance from the central notch k as to arrest the movement of the hand-lever I before said cam-plate is shifted sidewise a distance sufficient to bring its external side edges past the stud e . The parts or surfaces k^3 of said plate K outside of said shoulders $k^2\ k^2$ are located at such distance from the bar G as to prevent said lever I being thrown out far enough to disengage the cam-plate II from the stud e . Owing to the presence of said surfaces $k^3\ k^3$, therefore, the cam-plate can never be released from the stud, except when the hand-lever is between the shoulders $k^2\ k^2$ and it becomes necessary to throw the said hand-lever inwardly a distance sufficient to engage the cam-plate with the stud e before said cam-plate can be carried or moved sidewise from its central position a distance sufficient to bring the said stud e outside of or beyond its side margin. Said surfaces $k^3\ k^3$ therefore constitute a safety device to prevent the cam-plate ever being thrust inwardly when the stud e is outside of or beyond the flanges $H'\ H'$, thereby preventing the breakage of the parts which might result in case the machine were started with the said stud e outside of the cam-plate. Said cam-plate II is provided, as hereinbefore described, with two flat wings or plates $H^2\ H^2$, the faces of which are made flush with the surface or edge of the cam projections or flanges $H^1\ H^1$ which are nearest the worm-wheel E . Said wings H^2 serve to prevent the cam-plate being thrown toward the worm-wheel when the stud e is outside of the said cam-projections $H^1\ H^1$, the wings striking the end of the stud and preventing the plate from being moved inwardly until the said plate has been shifted back or forth in a direction to bring the stud between said cam projections. Said wings $H^2\ H^2$ may be made in some cases of such size or extended so far, as in a horizontal direction, that the stud e will never pass beyond the same in any position of the cam-plate. For compactness of con-

struction in the machine herein shown, however, the said wings H^2 H^3 are not made wide enough for this purpose; but the surfaces k^3 k^3 are employed to prevent the cam-plate from 5 being disengaged from the stud e , except when said cam-plate is at the middle part of its throw, or, in other words, except when the hand-lever is between the shoulders k^2 k^2 of the plate K.

- 10 The employment of the hand-lever I as a means of moving the cam-plate laterally is not essential, and said cam-plate may be actuated by means of a handle attached rigidly thereto or by any other suitable or convenient 15 means—as, for instance, in Fig. 13 I have shown said cam-plate as provided with a rigid handle L, bolted to the upper part of the plate, as shown. In the use of a handle of this kind obviously the same result will be 20 produced as when a pivoted hand-lever is used. The employment of a pivoted hand-lever connected with a cam-plate below the upper end of the same is, however, preferred in connection with the particular construction in the other parts illustrated, for the 25 reason that it affords better support to the cam-plate when the latter is sustained only at its top. As shown in said Fig. 13, the handle L affords pivotal support for the detent 30 J, and is so shaped as to engage with the plate K in the same manner as the hand-lever I, hereinbefore described.

I claim as my invention—

1. A reversing-gear comprising a revolving 35 pin or stud, a slide-bar, and a reciprocating cam-plate supported on said slide-bar and driven by said pin or stud, said cam-plate being mounted to slide laterally upon the slide-bar, whereby it may be moved bodily 40 toward and from the said pin or stud, substantially as described.

2. A reversing-gear comprising a revolving stud or pin, a slide-bar, and a reciprocating cam-plate supported on said slide-bar and 45 driven by the said stud or pin, said cam-plate being mounted to slide laterally on said slide-bar for engaging said cam-plate with and disengaging it from the said stud or pin, and a pivoted hand-lever for actuating said cam- 50 plate connected and moving with the latter, substantially as described.

3. A reversing-gear comprising a revolving

stud or pin, a slide-bar, a reciprocating cam-plate supported by said slide-bar and driven by the said stud or pin, said cam-plate being 55 mounted to slide laterally on said slide-bar for engaging said cam-plate with and disengaging it from said stud, and a detent connected and moving with the cam-plate and engaging the slide-bar for holding the cam-plate in position when engaged with or disengaged from the said pin or stud, substantially as described.

4. A reversing-gear comprising a revolving 65 stud or pin, a slide-bar, a reciprocating cam-plate driven by the said stud or pin, said cam-plate being mounted to slide laterally upon the slide-bar for engaging said cam-plate with and disengaging it from said stud or pin, a pivoted hand-lever connected with 70 said cam-plate, and a locking-plate provided with a central notch to receive said hand-lever, substantially as described.

5. A reversing-gear comprising a revolving 75 stud or pin, a reciprocating cam-plate driven by the said stud or pin and movable toward and from the said stud or pin, and a hand-lever or handle for moving said cam-plate, and a locking-plate provided with a central notch to receive said hand-lever or handle 80 and with surfaces at each side of said notch so located as to limit the outward movement of the cam-plate when the latter is free from the said stud or pin, except when the hand-lever or handle is engaged with the notch, 85 substantially as described.

6. A reversing-gear comprising a revolving 90 stud or pin, a reciprocating cam-plate driven by the said stud or pin and movable toward and from the said stud or pin for engaging 95 said cam-plate with and disengaging it from the same, and a locking-plate for the said lever provided with a central notch and with surfaces at its ends so located as to prevent the cam-plate being released from the said stud or pin, except at the middle part of its stroke, substantially as described.

In testimony that I claim the foregoing as my invention I affix my signature in presence of two witnesses.

GEORGE C. ROBERTS.
